UNITED STATES PATENT OFFICE.

JOSEPH WILLIAM SMITH, OF NEWTON, MASSACHUSETTS.

BUCKLE.

SPECIFICATION forming part of Letters Patent No. 298,511, dated May 13, 1884.

Application filed March 24, 1884. (No model.)

To all whom it may concern:

Be it known that I, JOSEPH WILLIAM SMITH, of Newton, in the county of Middlesex and State of Massachusetts, have invented a new and useful Improvement in Buckles, of which the following is a specification.

This invention relates to improvements in devices for securing the ends of straps or webbings to buckles or the like.

10 My invention consists in a metal plate having teeth formed on one edge, and adapted, when passed through a strap or webbing, to be bent back over the strap and the central part of the plate, and to be covered by bending back the other edge of the plate, in combination with a connecting-shank, as herein-after described, reference being had to the accompanying drawings, which illustrate various applications of my improved fastening, 20 and in which—

Figure 1 shows my fastening made from the cross-bar of a buckle. Fig. 2 shows it made from the middle bar of a slide. Fig. 3 shows a double-ended fastening. Fig. 4 shows the fastening adapted for a wire buckle. Fig. 5 is an end view showing the toothed edge and plane edge of the plate bent up, and Fig. 6 shows a fastening secured to the end of a webbing. Fig. 7 is a perspective view showing 25 my fastening attached to a wire buckle.

The plate A is formed with teeth a on one edge, the length of the teeth being approximately one-third the width of the plate A. The other edge a' of the plate is left plain, and 30 it, as well as the teeth, are bent up about at right angles to the central part of the plate A. The teeth are then passed through the strap or webbing, to be secured at the proper dis-

tance from the end, and are bent down or clinched over the end of the strap or webbing, 40 thereby securing it firmly to the central part of the plate A. The whole is then finished by bending back and forcing down onto the teeth the bent-up part of the edge a' . The fastening thus made is very firm and secure, and 45 presents a smooth, neatly-finished exterior. The width of the bent-up part of the plain edge a' is indicated by dotted lines in Figs. 1, 2, and 3, and is preferably such that when it is bent down over and parallel with the central part 50 of the plate, its edge will come flush with the bend in the teeth where they pass through the strap, and are bent back over its end. Shanks a^2 serve to connect the fastening to the buckle or slide. The connecting-shanks a^2 also form 55 the side bars of the buckler or slides. The teeth a may obviously be struck up from the central part of the plate, instead of projecting from its edge, and thereby make some saving in stock. It is better, however, to form the 60 teeth as shown in the drawings, and thereby keep the central part of the plate intact.

I claim as my invention—

A fastening for securing the ends of straps or webbings to buckles or the like, consisting 65 of a plate having one edge provided with teeth, adapted to bend back over the central part of the plate, and its other edge plain and adapted to fold back and cover the teeth when bent back over the central part of the plate, in 70 combination with a connecting-shank, a^2 , substantially as set forth.

JOS. WM. SMITH.
